J. T. COWLEY.

DEVICE FOR MOVING ARTICLES FROM ONE LEVEL TO ANOTHER.

APPLICATION FILED OCT. 8, 1915.

1,251,478.

Patented Jan. 1, 1918.

UNITED STATES PATENT OFFICE.

JAMES T. COWLEY, OF MINOT, MASSACHUSETTS, ASSIGNOR TO THE LAMSON COMPANY, OF BOSTON, MASSACHUSETTS, A CORPORATION OF NEW JERSEY.

DEVICE FOR MOVING ARTICLES FROM ONE LEVEL TO ANOTHER.

1,251,478.

Specification of Letters Patent.

Patented Jan. 1, 1918.

Application filed October 8, 1915. Serial No. 54,885.

To all whom it may concern:

Be it known that I, JAMES T. COWLEY, a citizen of the United States, residing at Minot, in the county of Plymouth and State 5 of Massachusetts, have invented certain new and useful Improvements in Devices for Moving Articles from One Level to Another, of which the following is a specification.

This invention relates to apparatus for 10 moving articles, such as crown bottle stoppers or the like, from one level to another by means of a belt conveyer or the equivalent thereof, and it has for one of its objects the handling of such articles while in transit 15 in such fashion as to prevent mutilation or scratching of the decorations or printing thereupon.

Another object of the invention is to provide a conveying mechanism which shall 20 deliver articles, properly emplaced therein for transit, so that said articles will all emerge from a part of the mechanism right side up, or each in a predetermined fashion, to permit, for example, of an inspection of 25 said articles or their delivery, all faced in a given way or direction, to some point which they are destined to pass.

More especially, and in its preferred embodiment, the invention has for its object the 30 transferring of crown stoppers, for example, from a lower to a higher level, sequentially while maintaining the stoppers properly faced preparatory to their inspection upon a preferably continuously moving part of 35 the mechanism.

These and other objects of my invention will be hereinafter referred to and the novel combinations of means and elements whereby 40 said objects may be attained will be more particularly set forth in the claims appended hereto.

In the drawing which forms a part hereof and in which like reference characters designate like parts in the respective views, I 45 have shown a preferred embodiment of my invention; but as I am aware of various changes and modifications which may be effected herein without departing from the spirit of my invention, I desire to be limited 50 only by the scope of said claims.

Referring to the drawing:

Figure 1 is a side elevation of a mechanism for elevating crown stoppers and permitting of the inspection of said stoppers.

Fig. 2 is an end elevation of said mechanism. 55

Fig. 3 is an enlarged detail transverse section of the inspection table, the section being taken on line III—III of Fig. 1; and

Fig. 4 is a similar section of the crown 60 elevator, taken on line IV—IV of Fig. 1.

The crown elevator preferably comprises two narrow and opposed belts 1 and 2 respectively arranged to pass around pulleys 3, 4, 5 and 6, and pulleys 5, 6, 7 and 8, in 65 a manner somewhat like that in which the cords or belts of a newspaper elevator are disposed.

When the opposed sides of the belts, which extend between the pulleys 5 and 6 are to 70 carry up, or even down, such articles as crown stoppers, however, the newspaper conveyer is not well adapted to such purpose, owing to the tendency for such relatively small objects to slip during transit and even 75 in some cases to overlap each other with consequent possible mutilation of the decoration or surface of the crown or like article when the opposed belt sections between which they ride travel in parallelism in 80 right lines or zig-zag around pulleys placed on alternate sides of said belt sections.

To provide means therefore which will firmly hold the crowns or the like in place 85 between the belts, presented a problem, which I have solved in an exceedingly simple manner. Upon inspecting Fig. 1 it will be observed that the opposed sections of the belts, between which the stoppers are carried, have been bowed out by a plate 9, the thickness 90 of which in Fig. 1, has been exaggerated, for clearness of illustration.

This plate or its equivalent may be suitably supported by cross-bars 10 which extend between and tie together the side 95 boards 11 between which the conveying sections of belts 1 and 2 ride.

The belt 1 is driven from the shaft 12 of pulley 3, as by means of a pulley 13 and belt 14, and while the frictional engagement between belts 1 and 2 will cause the former to drive the latter, if desired, and in order to reduce the tension in the belts, belt 2 may be separately driven from shaft 12 by pulleys 15 and 16 and a crossed belt 17. 100

The pulley 4 is preferably mounted upon a movable yoke or bracket 18, pivoted at 19 to the side of the elevator; a spring 20 tend-

ing to rotate the yoke counter-clockwise, as viewed in Fig 1, to place belt 1 under the desired tension.

Belt 2 is similarly tensioned by having its 5 pulley 8 journaled in a pivoted yoke 21, controlled by a spring 22.

The belts 1 and 2 are preferably grooved so that a recess is provided therebetween in which the crowns 23 are received, as shown 10 in Fig. 4; the sum of the depths of the opposed grooves (assuming, as is to be preferred, that both belts are grooved rather than to have a deeper groove in but one of them) being slightly less than the depth of 15 the article to be carried in order to aid in preventing slippage of the latter.

A chute 23' delivers the crowns or like articles to the horizontal run of the belt 1 adjacent said chute, so that the stoppers enter 20 the groove 24 in this belt in sequence and preferably with their corrugated edges up. They then, of course, travel along with belt 1 until these edges are received into the groove 25 in belt 2, whereupon the crowns 25 are clamped between the belts and travel upwardly past the bowed plate 9 which effectually prevents downward slippage of the stoppers, until they are carried around pulley 5 and delivered in order to the chute 26, 30 down which they slide onto the sorting table belt 27.

This latter travels somewhat slower than the belts 1 and 2, and preferably at about 17 feet per minute to permit of proper inspection 35 and sorting of the stoppers. The upper run of belt 27 rides in a groove in a support 28, one side of which is cut away, as at 29, to permit the inspectors to turn over the stoppers or sweep them off from the inspection belt onto the table 30 and vice versa, whenever desired.

Faulty stoppers or those having decorations not corresponding with the class being examined at any one time, which may inadvertently 45 get in, are removed, and the inspected articles then pass on to the chute 31 down which they descend to a mechanism not shown, since it forms no part of the present invention.

50 The inspection belt may be driven, if desired, from the shaft 12 by means of a belt or rope drive 32 and pulleys 33 and 34; but in any case and no matter how said inspection belt is driven, it should move at a speed 55 bearing a determined relation to that of the belts 1 and 2, to the end that the stoppers or like articles delivered to the inspection belt, shall not become congested.

In certain of the accompanying claims, I 60 have used the term belt or belts and wherever so used it is to be understood that such term is, of course, to comprehend equivalent devices such as cords and the like. In the preferred construction, flat belts are 65 used, the opposed article carrying portions

or sections of which tend, by virtue of the tensile stress imposed thereon, to shape or straighten the contacting surfaces, thereof, out into a determined and substantially vertical plane; said portions, however, being deformed from end to end thereof from the shape that they thus tend to assume, by the bowed or equivalently shaped plate 9, to prevent downward slippage of the article being carried between said portions. 75

Having thus described my invention what I claim is:

1. In means for elevating stoppers and the like, the combination of two tensioned belts driven at substantially the same speed, said belts having upwardly traveling extended portions thereof opposed to receive therebetween the articles being conveyed, and immovably mounted means to bow said opposed extended portions of said belts continuously both in the same direction to prevent slippage of said articles during transit. 85

2. In means for elevating stoppers and the like, the combination of two tensioned belts driven at substantially the same speed, 90 said belts having upwardly traveling extended portions thereof opposed to receive therebetween the articles being conveyed, and an extended, curved plate to bow said opposed extended portions of said belts both in the same direction to prevent slippage of 95 said articles during transit.

3. In means for conveying stoppers and the like from one level to another, the combination of two tensioned belts driven at 100 substantially the same speed, said belts having extended opposed and substantially vertical portions between which the articles to be carried are received, said portions each having a tendency to move into a determined 105 and substantially vertical plane, and means to curvilinearly deform said portions from the shape that they tend to assume in said plane, from substantially end to end thereof and continuously in a determined direction, 110 to prevent downward slippage of the articles being carried between said portions.

4. In means for conveying articles, the combination of two belts driven at substantially the same speed, said belts having opposed portions between which the articles to be carried are received, one at least of said portions being longitudinally grooved for the reception of a part of each article thereinto, means, located substantially wholly to 115 one side of the path of articles being conveyed, to prevent slippage of said articles along said grooved belt, and means to drive said belts.

5. In means for conveying articles, the 125 combination of two belts driven at substantially the same speed, said belts having opposed portions between which the articles to be carried are received, one at least of said portions having therein a continuous groove 1

extending longitudinally thereof, for the reception of parts of said articles thereinto, means, located along but one side of the path of travel of said articles between the ends of 5 said path, for pressing a wall of said groove firmly into engagement with articles being carried past said pressing means, and means for driving said belts.

6. In means for conveying articles, the 10 combination of two belts driven at substantially the same speed, said belts having opposed portions between which the articles to be carried are received, one at least of said portions having therein a continuous groove 15 extending longitudinally thereof, for the reception of parts of said articles thereinto, means, in sliding engagement with and acting upon at least one of said belts, to press a wall of said groove firmly into engagement 20 with articles being carried past said pressing means, the latter being located along the line of travel of said articles but out of their path, and means for driving said belts.

7. In means for moving articles from one 25 level to another, the combination of two tensioned belts having opposed article engaging portions to receive therebetween the articles

to be conveyed, and means, having a sliding engagement with and acting upon one of said belts to thereby bow both belts laterally 30 in the same direction to prevent slippage of said articles during their passage past said bowing means.

8. In means for conveying articles, the combination of two belts driven at substantially 35 the same speed, said belts having opposed portions between which the articles to be carried are received, one at least of said portions having therein a continuous groove 40 extending longitudinally thereof, for the reception of parts of said articles thereinto, means, located along the path of travel of said articles between the ends of said path, for substantially continuously pressing a wall 45 of said groove firmly into engagement with articles being carried, and means for driving said belts.

In testimony whereof I have affixed my signature, in the presence of two witnesses.

JAMES T. COWLEY.
